(57) **CLAIM**

The ornamental design for a brake pedal for a firearm, as shown and described.

DESCRIPTION

FIG. 1 is a top front perspective view of a brake pedal for a firearm, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a reduced top front perspective view of the brake pedal for a firearm shown in a used condition.

The dash-dash broken lines showing the firearm in FIG. 8 depicts environmental subject matter and forms no part of the claimed design, while the remaining dash-dash broken lines shown in the drawings depicts portions of the brake pedal for a firearm that form no part of the claimed design. The dot-dash-dot broken lines shown in the drawings depicts the bounds of the claimed design and forms no part of the claimed design.

1 Claim, 5 Drawing Sheets
